UNITED STATES PATENT OFFICE.

BURT J. PRESSEY, OF NEWPORT NEWS, VIRGINIA.

AEROPLANE.

1,081,147.

Specification of Letters Patent.

Patented Dec. 9, 1913.

Application filed November 19, 1908. Serial No. 463,460.

To all whom it may concern:

Be it known that I, BURT J. PRESSEY, a citizen of the United States, residing in Newport News, Virginia, have invented certain Improvements in Aeroplanes, of which the following is a specification.

My invention consists of certain improvements in or additions to the aeroplane forming the subject of my application for patent filed October 17, 1908, Serial No. 458,234.

One of the objects of my present invention is to control, by means of one and the same swinging weight (preferably, the aviator's seat) the operation both of the planes for 15 correcting lateral dip and those for correcting longitudinal dip of the main plane, another object being to render the longitudinal dip-correcting planes inoperative during ascent or descent of the main plane, a further object being to combine automatic control 20 of the lateral dip-correcting means with manual operation of longitudinal dip-controlling means, and a still further object being to relieve the aviator from the care 25 of the manually-operated longitudinal dip-controlling means when a level and course of flight have once been established. These objects I attain in the manner hereinafter set forth, reference being had to the accompanying drawings, in which—

Figure 1 is a perspective view of an aeroplane constructed in accordance with my present invention; Fig. 2 is a vertical longitudinal section of the same, and Fig. 3 is a vertical transverse section.

As in my former application, I have, for the purpose of illustrating my invention, selected an aeroplane having upper and lower main planes 1 and 2, but it should be understood that the main features of my invention are not limited to aeroplanes of this type but may be applied to aeroplanes generally, whether provided with a single main plane or with a plurality of such planes, and I will hereinafter, for convenience, refer to this element as a "main plane."

The invention is intended for use in connection with that type of aeroplanes in which the propelling mechanism is carried by the main plane, as shown in Fig. 2.

As in the invention forming the subject of my former application, the main purpose

is to correct lateral and longitudinal dip of the main plane when the latter is in flight. 55

The aeroplane is equipped with a manually-operated vertical steering plane 3 at the stern, and it has, at the bow, a horizontal manually-operated longitudinal-dip-controlling plane 4.

Near each end of the upper main plane 1 is a supplemental plane 5 of such surface area as experience may prove to be necessary, these supplemental planes being shown in Fig. 1 as located within the area of the 65 main plane, although this is not essential. In connection with these supplemental planes 5, I employ a gravity-influenced weight for holding them in a horizontal or substantially horizontal position when the 70 main plane is traveling on an even keel, and for causing them to tip when the main plane dips laterally to port or starboard, the supplemental planes having a lifting effect upon the depressed end of the main plane and a 75 depressing effect upon the lifted end of the same so as to tend to correct such lateral dip of the main plane and restore it to an even keel.

The gravity-influenced weight which I 80 prefer to employ is the aviator's seat 6, which is carried by a yoke 7 depending from a fore and aft shaft 9, the latter being pivotally mounted in bearings at the ends of a bar 10, which is secured to a transverse 85 shaft 11, pivotally mounted at its ends in suitable bearings depending from the main plane 1, thus providing a gimbal joint which permits free tipping movement of the main plane both in a lateral direction and in a 90 fore and aft direction in respect to said seat, when not otherwise restrained, the seat having a normal tendency to hang vertically from its supports by reason of the effect of gravitation upon the weight represented by 95 the seat and its occupant.

Lateral tipping of the main plane is caused to effect corrective movement of the supplemental planes 5 in the following manner: Each of said supplemental planes is 100 carried by a transverse rock shaft 12, suitably pivoted in bearings depending from the main plane 1 and having at its inner end an arm 13 which is bent forwardly at the lower end and enters a slot in one arm of a bell 105 crank lever 14, the latter being pivotally

mounted upon a fore and aft pin on the main plane 1, and the other arms of the port and starboard levers 14 being connected together by a rod 15 which has an eye 16 for the entrance of a segmental rod 17 secured to and projecting forwardly from a cross bar on the seat-suspending yoke 7. When, therefore, the main plane tips downwardly on the starboard side the rod 15 will 10 be moved bodily to starboard and the starboard supplemental plane 5 will be tipped so as to raise its forward end and depress its after end, while at the same time the port supplemental plane 5 will be tipped so as to 15 depress its forward end and raise its after end, thereby causing the starboard supplemental plane to exercise a lifting effect and the port supplemental plane to exercise a depressing effect upon the main plane, with 20 the effect of restoring the same to an even keel.

When the main plane dips downwardly on the port side a reverse action takes place with the like result of restoring the main plane to an even keel. In order to correct 25 fore and aft dip of the main plane I provide fore and aft supplemental planes 19 and 20, carried by transverse rock shafts which may be pivotally mounted in any suitable way 30 upon structures carried by the main plane. In the present instance, the forward supplemental plane 19 is pivotally mounted in extensions 21 of the frame 22 which carries the forward manually-operated longitudinal-dip-controlling plane 4, and the rear supplemental plane 20 is pivotally mounted in a 35 yoke 23 secured to the upper frame 24 to which the vertical steering plane 3 is pivoted.

Projecting upwardly from the bar 10 is 40 an arm 25 which is connected by rods or links 26 to an arm 27 projecting upwardly from the forward supplemental plane 19 and to an arm 29 projecting downwardly from 45 the aft supplemental plane 20. When, therefore, there is a downward dip of the fore part of the main plane, retention of its vertical position by the arm 25 will cause the forward supplemental plane 19 to tip so as 50 to raise its forward edge and depress its after edge, while at the same time the after supplemental plane 20 will tip so as to depress its forward edge and raise its after edge, with the result that there will be a 55 lifting action on the fore part of the main plane and a depressing action on the after part of the same, tending to restore said main plane to an even keel, a reverse action taking place when the after part of the 60 main plane has a tendency to dip.

By the term "an even keel" in respect 65 to the fore and aft position of the main plane I do not mean a horizontal position of the main plane but such a rearward dip of the same as may be necessary to permit the

air to exercise the required supporting effect thereon, the longitudinal dip which the supplemental planes 19 and 20 are intended to correct being a departure from this normal inclination, which, in the case of a forward dip would cause the main plane to descend from its normal level of flight and in the case of an aft dip would cause it to rise from such level. In ascending or descending, however, such departures from the normal inclination of the plane when in flight are necessary, and in order that the supplemental planes 19 and 20 may not interfere with intentional ascent or descent the aviator's seat or other controlling weight 70 should, in making such ascent or descent, be practically locked to the main plane as regards fore and aft dip. This may be effected by providing stirrups 30 on the lower plane 75 2 for the reception of the aviator's feet, the latter being withdrawn from the stirrups when the proper level of flight has been attained. In order, however, to provide a more rigid locking of the seat to the main plane I prefer to provide said seat with one 80 or more bolts, whereby it may be locked to the lower member of the plane so far as regards fore and aft dip of the latter, while still having a free pivotal connection with the upper member of the plane so far as regards lateral dip of the latter. In the present instance I have shown one of such bolts 85 31 at each side of the seat 6, each bolt being adapted to a transverse slot 32 in the lower member 2 of the plane and being vertically 90 guided in a tubular casing 33 depending from the seat 6. Each bolt has, at the upper end, a handle 34, whereby it may be conveniently manipulated, and it is normally retained in the elevated or unlocking position by means of a coiled spring 35, but can be held in the depressed or locking position by engagement of a pin 36 on the bolt with the lower end of an angular slot 37 formed in the bolt case or guide 33, as shown in 95 Fig. 2.

The forward longitudinal-dip-controlling plane 4 is manually operated by means of a lever 40 pivotally mounted upon a bearing 41 depending from the upper member 1 of the plane and connected by a rod or link 42 to an arm 43 projecting upwardly from said forward plane 4, and, in like manner the vertical steering plane 3 is manually operated by means of a lever 44 hung to a depending bearing 45 and connected by a rod or link 46 to an arm 47 projecting laterally from said vertical steering plane 3.

In order that the aviator may be freed 125 from the necessity of maintaining his hold upon the levers 40 and 44 when the level and course of the aeroplane have once been established, I provide means for locking said levers 40 and 44 in different positions of adjustment. Many different means may be 130

used for this purpose, but in the drawing I have shown, mounted upon each of the levers 40 and 44, a spring-actuated lever 50 having a bolt 51 which can engage with any one of a series of segmentally arranged openings in the sector shaped lower end 52 of the bearing to which the lever is hung.

The segmental arm 17 is concentric with an axis co-incident with that of the transverse shaft 11, hence said arm is free to move through the eye 16 on the rod 15 whenever there is fore or aft dip of the main plane, yet said rod 15 at once responds to any lateral dip of said main plane so as to impart 15 to the port and starboard supplemental planes 5 the movement necessary to correct such dip.

While I have shown, my invention as applied to an aeroplane having independent 20 dip-correcting supplementary planes at the port and starboard sides of the main plane it will be evident that the invention is equally applicable to the well known Wright aeroplane, or to planes of the character 25 shown in the patent of O. and W. Wright, No. 821,393, dated May 22, 1906, and many other variations in the details of construction may be made within the scope of my invention.

I claim:

30 1. An aeroplane having a universally swinging and gravity-influenced weight, means for correcting lateral dip of the main plane, means for correcting longitudinal dip of said main plane, connections between said dip-correcting means and said universally swinging weight whereby the latter constitutes the motive power for operating said dip-correcting means, and manually operated longitudinal dip-controlling means independent of the dip-correcting means, all of said dip-correcting and controlling means comprising surfaces adjustable to different angles of incidence to the air flowing past the plane.

45 2. An aeroplane having fore and aft supplemental planes, a swinging and gravity-influenced aviator's seat connected to said planes and causing them to act together to correct longitudinal dip of the main plane, 50 and a manually operated plane for controlling such longitudinal dip.

3. An aeroplane having means for correcting lateral dip thereof, means for correcting longitudinal dip, a universally swinging weight, means connecting said weight to said longitudinal and lateral dip-correcting means, whereby it serves as the motive power for operating the same and permits operation of the longitudinal-dip-correcting means independently of the lateral-dip-correcting means and vice-versa, and manually operated longitudinal dip-controlling means, independent of the dip-correcting means, all of said dip-correcting 65 and controlling means comprising surfaces

adjustable to different angles of incidence to the air flowing past the plane.

4. An aeroplane having, at port and starboard, means for correcting lateral dip of the main plane, a transverse rod connecting 70 said means, and a universally-swinging and gravity-influenced weight for operating the same, the suspending devices for the weight having a rod-operating arm concentric with the transverse axis of said suspending devices, whereby the longitudinal dip of the main plane is prevented from affecting the position of the lateral-dip-correcting means.

5. An aeroplane having, in combination, 75 a main plane, a gravity-influenced and universally-swinging weight, a bolt carried by one of said parts and adapted to engage the other part so as to prevent forward or aft dip of the plane independently of the weight, means connected with the weight 80 for correcting lateral dip of the main plane, means connected with the weight for correcting longitudinal dip of the main plane, and means for engaging and disengaging the bolt, whereby, while the weight is continuously operative to actuate the means for correcting lateral dip, it may be rendered operative or inoperative to actuate the means for correcting longitudinal dip.

6. An aeroplane having, in combination, 85 a main plane, a gravity-influenced and universally-swinging weight, a bolt carried by one of said parts, and adapted to enter a lateral slot in the other part, means connected to the weight for correcting lateral 90 dip of the main plane, means connected to the weight for correcting longitudinal dip of said main plane, and means for engaging and disengaging the bolt and slot, whereby the weight, while continuously operative to 95 actuate the means for correcting lateral dip, may be rendered operative or inoperative to actuate the means for correcting longitudinal dip.

7. In an aeroplane, the combination of a 100 main plane, propelling devices carried thereby, lateral-dip-correcting means, a laterally swinging aviator's seat, and means for connecting the same to said lateral-dip-correcting means, whereby it serves as the motive 105 power for operating the latter.

8. The combination, in an aeroplane, of 110 a main plane, lateral-dip-correcting means, longitudinal-dip-correcting means and longitudinal-dip-controlling means, all comprising surfaces adjustable to different angles of incidence to the air flowing past the plane, a gravity-influenced weight for operating the lateral-dip-correcting means, and longitudinal-dip-correcting means, and 115 manually-operated devices independent of said weight for actuating the longitudinal-dip-controlling means.

9. The combination, in an aeroplane, of 120 the main plane, lateral-dip-correcting means, 125

longitudinal-dip-correcting means, and longitudinal-dip-controlling means, all comprising surfaces adjustable to different angles of incidence to the air flowing past the plane, a gravity-influenced and universally swinging weight, connections whereby the latter may be caused to operate both the lateral and longitudinal - dip - correcting means, and manually-operated devices independent of said weight for actuating the longitudinal-dip-controlling means.

10. In an aeroplane, the combination of a main plane, propelling devices carried thereby, lateral-dip-correcting means, longitudinal-dip-controlling means, a laterally swinging aviator's seat, connections whereby the same is caused to operate the lateral-dip-correcting means, and manually-operated devices for actuating the longitudinal-dip-controlling means.

11. In an aeroplane, the combination of the main plane, lateral-dip-correcting means, longitudinal-dip-correcting means, longitudinal-dip-controlling means, a universally swinging and gravity-influenced aviator's seat, connections whereby the same is caused to operate both the lateral and the longitudinal dip-correcting means, and manually-operated devices for actuating the longitudinal-dip-controlling means.

12. The combination, in an aeroplane, of the main plane, longitudinal-dip-correcting means and longitudinal - dip - controlling means, both comprising surfaces adjustable to different angles of incidence to the air flowing past the plane, a gravity-influenced weight, means whereby the same is caused to actuate the longitudinal-dip-correcting means, and manually operated devices independent of the weight for actuating the longitudinal-dip-controlling means.

13. The combination, in an aeroplane, of the main plane, longitudinal-dip-correcting means, longitudinal-dip-controlling means, a gravity-influenced weight, means whereby the same is caused to actuate the longitudinal-dip-correcting means, means for rendering said weight operative or inoperative, at will, and manually-operated devices for actuating the longitudinal-dip-controlling means.

14. The combination, in an aeroplane, of the main plane, longitudinal-dip-correcting means, longitudinal-dip-controlling means, a gravity-influenced aviator's seat, means whereby the same is caused to actuate the

longitudinal-dip-correcting means, and manually-operated devices for actuating the longitudinal-dip-controlling means.

15. The combination, in an aeroplane, of 60 the main plane, longitudinal-dip-correcting means, longitudinal-dip-controlling means, a gravity-influenced aviator's seat, means whereby the same is caused to actuate the longitudinal - dip - correcting means, means 65 for rendering the said seat operative or inoperative at will, and manually-operated devices for actuating the longitudinal-dip-controlling means.

16. The combination, in an aeroplane, of 70 75 the main plane, lateral-dip-correcting means, longitudinal-dip-correcting means, longitudinal-dip-controlling means, a universally swinging and gravity-influenced weight, connections whereby the latter may be caused to operate both the lateral and the longitudinal dip-correcting means, devices for rendering said weight operative or inoperative at will, as the means for actuating the longitudinal-dip-correcting means, and 80 manually operated devices for actuating the longitudinal-dip-controlling means.

17. The combination, in an aeroplane, of 85 the main plane, lateral-dip-correcting means, longitudinal-dip-correcting means, longitudinal-dip-controlling means, a universally swinging and gravity-influenced aviator's seat, connections whereby the latter may be caused to operate both the lateral and the longitudinal dip-correcting means, devices 90 for rendering the seat operative or inoperative at will, as the means for actuating the longitudinal-dip-correcting means, and manually-operated devices for actuating the longitudinal-dip-controlling means. 95

18. In a flying machine, a horizontal aeroplane, a forward horizontal rudder above said aeroplane, and a rear horizontal rudder above the aeroplane.

19. In a flying machine, a horizontal aeroplane, a forward horizontal rudder above the aeroplane, a rear horizontal rudder above the aeroplane, and means for accomplishing a simultaneous adjustment of the forward and rear horizontal rudders. 100 105

In testimony whereof, I have signed my name to this specification, in the presence of two subscribing witnesses.
